UNITED STATES PATENT OFFICE.

JAMES M. SCHWARTZ, OF NEW YORK, N. Y.

DESIGN FOR A GAME-BOARD.

SPECIFICATION forming part of Design No. 26,186, dated October 13, 1896.

Application filed September 4, 1896. Serial No. 604,905. Term of patent 3½ years.

To all whom it may concern:

Be it known that I, JAMES M. SCHWARTZ, a citizen of the United States, residing at the city of New York, in the county and State of New York, have invented and produced a new and original Design for a Game-Board, of which the following is a specification, reference being had to the accompanying drawings, forming part thereof, and in which—

Figure 1 is a top view of a game-board bearing my design, and Fig. 2 is a sectional view of same on the dotted line 2 2 of Fig. 1.

The leading features of my design consist of the form and configuration of the various passages intermediate, the outer or starting space, and the central or home space, substantially as shown and described.

In the drawings, A designates the board; B, the outer or starting space; C, the central or home space; D, the various passages or grooves intermediate the spaces B C, and E the elevations along and outlined by said grooves or passages.

What I claim is—

The design for a game-board, substantially as shown and described.

Signed at New York, in the county and State of New York, this 2d day of September, 1896.

JAMES M. SCHWARTZ.
